UNITED STATES PATENT OFFICE.

EBENEZER HILL, OF NORWALK, CONNECTICUT.

AIR-COMPRESSOR CONTROL.

1,262,667.

Specification of Letters Patent. Patented Apr. 16, 1918.

Application filed November 1, 1916. Serial No. 128,861.

To all whom it may concern:

Be it known that I, EBENEZER HILL, a citizen of the United States, residing at Norwalk, in the county of Fairfield and State of Connecticut, have invented a new and useful Improvement in Air-Compressor Controls, of which the following is a specification.

This invention relates to means for controlling the effective action of multiple-stage power-driven air and gas compressors, particularly compressors which are capable of furnishing air at high pressures.

The object of the invention is to so arrange and control the air connections of such a compressor that without stopping the machine the high pressure cylinder can be thrown into or out of effective action, and thereby provide one machine which will deliver the desired supply of air or gas economically at high pressure or low pressure as the exigencies of the case require.

This invention is especially valuable for compressors designed to be used in the processes of liquefying air; breaking up atmosphere and separating the gaseous elements,—as in segregating oxygen and nitrogen; and in the atmospheric fertilizer making processes, in which a relatively small quantity of air compressed to a high degree, for instance, 3,000 pounds and upward, is used at times to quickly obtain a very low temperature, and after the temperature has been reduced to the desired point the operation can be continued efficiently with the main supply of air at considerably lower pressure, for instance, 800 pounds. In practising these processes it has been common to employ two compressors, one for obtaining the extremely high pressure which is used only a small part of the time, and another for producing the lower pressure which is used practically all of the time, and when the demand for high pressure ceases the high pressure machine is shut down and remains idle while the compressor of lower pressure is worked.

The object of this invention is attained by utilizing a high pressure compressor and providing a by-pass for the high pressure cylinder, which by-pass is controlled by a valve that may be operated manually or automatically by air pressure in the high or low pressure receivers, or by the speed of the compressor or the motor which drives it, or by the temperature in the air line at the compressor or other apparatus employed in the

processes, or by any desired combination of these agencies as the particular conditions suggest to be the most satisfactory.

The invention is illustrated and described herein in connection with a four-stage compressor having three cylinders proportioned for supplying the required amount of air at the lower pressure, or pressure at which the machine is to be run continuously, and having a fourth cylinder which can, when desired, be immediately made effective to raise the pressure from the third inter-cooler pressure to the high pressure required, but the invention is obviously equally applicable to a three-stage or a two-stage compressor.

Figure 1 of the accompanying drawings shows diagrammatically a side elevation of the cylinders, inter-coolers and air connections of a four-stage compressor, with the cylinders so connected that the desired supply of air or gas may be raised to a high pressure or to a lower pressure according to the demand, the change being made from high to lower pressure or from low to higher pressure without stopping the machine by manually operating a valve in a by-pass around the high pressure cylinder. The cylinder valves, cooling water connections and pistons are not shown, as they are of ordinary construction and are well understood by those skilled in this art. Fig. 2 shows on larger scale the high pressure cylinder with a by-pass valve that can be automatically operated according to predetermined conditions by electrical means controlled by the pressure in the high and low pressure receivers, or by the temperature of the air in the line, or by the speed of the compressor. Fig. 3 shows the high pressure cylinder with a by-pass valve that is designed to be automatically opened on the occurrence of an abnormal rise in the high pressure receiver and on the occurrence of an abnormal drop in the low pressure receiver.

In the type of machine illustrated the first or low pressure cylinder 1 is usually attached to the second or next higher pressure cylinder 2, and the third or next higher pressure cylinder 3 is usually attached to the fourth or high pressure cylinder 4, with the axes of the cylinders in line. The inter-cooler 5 connects the discharge of the first cylinder with the intake of the second cylinder; the inter-cooler 6 connects the discharge of the second cylinder with the intake of the third cylinder; and the inter-cooler 7 connects the

discharge of the third cylinder with the intake of the fourth cylinder in the ordinary way. The air or gas enters through the intake 8 of the first cylinder and is pumped from that cylinder through the pipe 9 into the inter-cooler 5 where it is cooled. From this inter-cooler the air is drawn through the pipe 10 to the second cylinder and is pumped from that cylinder through the pipe 11 into the inter-cooler 6 where it is again cooled. From the inter-cooler 6 the air is drawn through the pipe 12 to the third cylinder, from which it is pumped through the pipe 13 to the inter-cooler 7. After passing through the inter-cooler 7 and being cooled therein the air is drawn through the pipe 14 to the fourth cylinder and is pumped therefrom through the discharge pipe 15 to the high pressure receiver 16 if the conditions are such that the machine is to supply air at high pressure. In the discharge pipe from the high pressure cylinder is an outwardly opening check-valve 17, and passing from the intake pipe 14 of the high pressure cylinder to the discharge pipe 15 of the high pressure cylinder around the high pressure cylinder is a pipe 18 in which is a stop-valve. In the embodiment of the invention shown in Fig. 1 the stop-valve is illustrated as a manually operated cock 19. The low pressure receiver 20 is connected with the pipe 14 between the third inter-cooler and the fourth cylinder by a pipe 21. The pistons in the interior of the cylinders are connected as usual by a piston rod 22 which is reciprocated by a link 23 connected with the crank 24 on the shaft 25 which has the fly-wheel 26. In the machine illustrated the crank and fly-wheel shaft has a driving pulley 27, which is belted to a pulley 28 on the armature shaft 29 of an electric motor 30. While the compressor is illustrated as motor driven, it could, of course, as is common, be engine driven.

When the machine is working with the valve 19 closed the air or gas is successively raised in the four cylinders from atmospheric pressure to the highest pressure which, of course, depends upon the proportions of the several cylinders, and this air is forced at the third pressure into the low pressure receiver 20, and at high pressure past the check-valve 17 into the high pressure receiver 16. When the need for high pressure air ceases the valve 19 is opened by hand. This puts the high pressure cylinder out of commission, the air merely being pumped around it through the by-pass pipe. Under this condition all the air which comes from the third inter-cooler at the pressure to which it is raised by the first three cylinders is pumped at that pressure into the low pressure receiver, and the compressor will continue to furnish air at the lower pressure

through the low pressure discharge line as long as the by-pass valve 19 is open. At this time the air at high pressure in the high pressure line is held from coming back by the check-valve 17. Thus by closing the stop-valve 19 the machine may be made to deliver air at the highest pressure for which it is designed, or by opening the valve 19 the machine may be made to deliver all the air at the lower pressure only. This arrangement is valuable for all multiple-stage compressors where it is desirable to operate the machines only a small part of the time for supplying the high pressure air.

In the arrangement shown in Fig. 2 an automatically operated valve 31 is shown as placed in the by-pass 18 from the intake 14 to the discharge 15 of the high pressure cylinder 4. As in the case with the hand operated valve, when this automatically operated valve is closed the high pressure cylinder is effective and supplies air at high pressure, and when this valve is open the high pressure cylinder is rendered ineffective, and all of the air is available for the lower pressure. The valve 31 is of a balanced type having two ports 32 adapted to be closed by disks 33 mounted on a stem 34 that is connected with the core 35 of a solenoid 36. A spring 37 is arranged to normally lift the solenoid core and keep the valve open. When the solenoid is excited by the flow of current the core is drawn down and the valve is closed. One terminal 38 of the solenoid winding may be connected by a lead 39 with a battery 40 or other source of electrical energy. The other terminal 41 of the solenoid winding is connected by a lead 42 with various gages designed, as the predetermined conditions arise, to open and close the circuit, including the source of energy and the solenoid. The lead 42 is shown as running to a terminal 43 of a pressure gage 44, the other terminal 45 of which is connected with a terminal 46 of a pressure gage 47. The second terminal 48 of the latter gage is connected with the terminal 49 of a tachometer 50, whose second terminal 51 is connected by a lead 52 with the battery. The lead 42 is also shown as connected with the terminal 53 of a thermometer gage 54, the second terminal 55 of which is connected with the terminal 49 of the tachometer 50.

The pressure gages 44 and 47 are of a common type, the former being connected by pipe 56 with the high pressure side of the air line beyond the high pressure cylinder, and the latter being connected by pipe 57 with the lower pressure side of the air line before the high pressure cylinder. These pressure gages are set in the well known way so as to open and close the electric circuit at the selected pressures.

The tachometer 50 and the thermometer

54 are of a common type. The former may have its flexible drive shaft 58 connected with any suitable moving part of the compressor, the speed of which is to be utilized to control the opening and closing of the by-pass valve, and the latter may have its flexible pressure tube 59 connected with the expansion tube 60 which may be located in any part of the system, the temperature of which it is desired to utilize to control the opening and closing of the by-pass valve. The tachometer and thermometer are set in the well known way, so as to open and close the electric circuit at the predetermined speeds and temperatures.

The contact of the tachometer or speed regulator can be set at any speed which is desired to have the compressor run. If the compressor is not up to speed the hand of this instrument is off the contact and the circuit is broken, and when the circuit is broken the compressor through the opening of the automatic valve is unloaded of the high pressure cylinder. When the compressor gets up to speed the hand of the tachometer closes the circuit, then any of the other regulators can take hold and control the pressures. This permits the motor to be started up with but a light load. If for any reason after the pressure controls take hold and are regulating the compressor anything happens which slows the compressor down, the tachometer hand will move off from its contact and break the circuit, and thus again unload the compressor of the high pressure cylinder until the normal speed is resumed.

When the compressor is starting up and there is no pressure the by-pass valve will remain open and the high pressure cylinder will not pump into the line. The hands on the pressure gages, however, will rise together as the pressure creeps up. Whenever the pressure which is desired on the low pressure side is reached, say for instance, 800 pounds, the contacts will be closed on both gages, and as they are in series current will pass through the solenoid and close the by-pass valve. The compressor will then continue to work with the high pressure cylinder in commission as long as the pressure on the low pressure side keeps up to the predetermined normal. This will continue until the pressure on the high pressure side reaches its predetermined point, say, 3,000 pounds, when the contact on the high pressure gage will be broken and the circuit opened, so that the by-pass valve will be lifted by its spring and the high pressure air cylinder will again be unloaded and all the air will be pumped into the low pressure receiver.

The thermometer gage will control the by-pass valve through the solenoid and the

tachometer according to the temperature of any part of the compressor or apparatus connected to it in any way that it is desired to utilize for the purpose.

In order to control the by-pass by an abnormal rise in the high pressure receiver, or an abnormal drop in the low pressure receiver, resulting from the demands for air at different pressures, an automatic by-pass valve 61 may be arranged in the by-pass pipe 18 that extends from the intake 14 to the discharge 15 around the high pressure cylinder 4. This valve has a closing disk 62 with a stem 63 attached to a plunger 64. Opening into the plunger chamber below the plunger is a passage 65 connected by a pipe 66 which opens into a chamber 67 of an air control. This air control has a valve 68 that is normally held closed by a spring 69 which is placed on the stem 70 of the valve. The intake pipe 71, which is connected with the high pressure pipe 15 beyond the check-valve 17, is normally kept closed by the valve 68. If the pressure should rise abnormally high in the high pressure receiver, or for instance, to 3,500 pounds, that pressure will open the air control valve 68 and allow the high pressure air to flow through the pipe 66 and raise the plunger 64 so as to lift the valve 62 from its seat. When this valve is lifted from its seat the by-pass is opened so that the high pressure cylinder is cut out and all of the air will be pumped to the low pressure receiver 20. When the pressure on the high pressure side drops to normal the control valve is closed by its spring and the by-pass valve allowed to shut and again put the high pressure cylinder into commission. The low pressure side of the system is connected by a pipe 72 with a control 73. This control has a plunger 74 that is normally pressed down by a spring 75, the spring being adjusted to such a degree that when the pressure on the low pressure side is normal the plunger 74 is held raised by that pressure. If, however, the pressure on the low pressure side drops below normal, for instance, below 750 pounds, the spring 75 will force the plunger 74 downward and its stem 76 will rock the lever 77 and cause it to lift the stem 70 of the valve 68. When this is lifted, as before stated, the high pressure air passes through the control and raises the plunger 64 so as to lift the by-pass valve 62 from its seat and open the by-pass. Under these conditions the by-pass will remain open and no air will be forced forward from the high pressure cylinder until the pressure in the low pressure receiver is again raised to normal.

By means of this simple invention the high pressure cylinder of a multiple-stage compressor can be made effective or can be

rendered ineffective by the manipulation of a manually operated or an automatically operated by-pass valve. The automatic regulation can be controlled by pressure or 5 temperature or speed or a combination of these agencies. The pressure utilized can be that of the high or low pressure receivers, or both. The speed control can be conditioned on the movement of parts of the 10 motor or compressor, and the temperature utilized may be that in either of the air lines or the fluid operated upon in any part of the system.

The automatic valve may be opened to 15 by-pass the high pressure cylinder when the high pressure becomes abnormally high, or when the low pressure becomes abnormally low. Controlling by the compressor speed allows the motor to start up with a relatively light load and to keep up the speed if the load should become sufficiently high to cause an undue strain on the motor. When the temperature rises in the system and it is desired to secure a greater supply 20 of air at high pressure so as to obtain a quick drop, the by-pass valve is closed, and when the temperature drops to the desired degree so that the system will operate efficiently with air at lower pressure, the by-pass is opened so as to cut out the high pressure cylinder, thus economizing in power. By utilizing this invention one machine may be efficiently employed where it has previously been thought to be necessary 25 to employ two machines, one for very high pressure and one for moderate pressure.

The invention claimed is;

1. In an air compressor the combination of a low pressure cylinder having an intake 40 and discharge, a high pressure cylinder having an intake and discharge, a connection between the discharge of the low pressure cylinder and the intake of the high pressure cylinder, a low pressure receiver connected with said connection between the cylinders, a high pressure receiver connected 45 with the discharge of the high pressure cylinder, a return-pass between the connections to the low and high pressure receivers, a stop-valve in said return-pass, and a back-check-valve in the connection between the discharge of the high pressure cylinder and the high pressure receiver beyond the point of connection of the return-pass, whereby when said stop-valve is open 50 air will be pumped into the low pressure receiver but not into the high pressure receiver.

2. In an air compressor the combination of a low pressure cylinder having an intake 60 and discharge, a high pressure cylinder having an intake and discharge, a connection between the discharge of the low pressure cylinder and the intake of the high pressure cylinder, a low pressure receiver 65 connected with said connection between the cylinders, a high pressure receiver connected with the discharge of the high pressure cylinder, a return-pass between the connections to the low and high pressure receivers, a stop-valve in said return-pass, electro-magnetic means controlled by the pressures of air in the high 70 pressure and low pressure receivers for controlling the closing and opening of said stop-valve, and a back-check-valve in the connection between the discharge of the high pressure cylinder and the high pressure receiver.

connected with said connection between the cylinders, a high pressure receiver connected with the discharge of the high pressure cylinder, a return-pass between the connections to the low and high pressure receivers, a stop-valve in said return-pass, mechanism controlled by the pressure of air in the high pressure receiver for closing and opening said stop-valve, and a back-check-valve in the connection between the 75 discharge of the high pressure cylinder and the high pressure receiver beyond the point of connection of the return-pass, whereby when said stop-valve is open air will be pumped into the low pressure receiver but 80 not into the high pressure receiver and when said stop-valve is closed air will be pumped from the low pressure cylinder into the low pressure receiver and from the high pressure cylinder into the high pressure receiver.

3. In an air compressor the combination of a low pressure cylinder having an intake and discharge, a high pressure cylinder having an intake and discharge, a connection between the discharge of the low pressure cylinder and the intake of the high pressure cylinder, a low pressure receiver connected with said connection between the cylinders, a high pressure receiver connected 95 with the discharge of the high pressure cylinder, a return-pass between the connections to the low and high pressure receivers, a stop-valve in said return-pass, electro-magnetic means controlled by the pressure 100 in the high pressure receiver for controlling the closing and opening of said stop-valve, and a back-check-valve in the connection between the discharge of the high pressure cylinder and the high pressure receiver beyond the point of connection of the return-pass, whereby when the pressure in the high pressure receiver rises above normal said stop-valve is opened and air will be pumped into the low pressure receiver but not into 110 the high pressure receiver.

4. In an air compressor the combination of a low pressure cylinder having an intake and discharge, a high pressure cylinder having an intake and discharge, a connection 115 between the discharge of the low pressure cylinder and the intake of the high pressure cylinder, a low pressure receiver connected with said connection between the cylinders, a high pressure receiver connected with the discharge of the high pressure cylinder, a return-pass between the connections to the low and high pressure receivers, a stop-valve in said return-pass, electro-magnetic means controlled by the pressures of air in the high 120 pressure and low pressure receivers for controlling the closing and opening of said stop-valve, and a back-check-valve in the connection between the discharge of the high pressure cylinder and the high pressure receiver 125.

beyond the point of connection of the return-pass, whereby when the pressure in the high pressure receiver rises above normal or the pressure in the low pressure receiver drops below normal said stop-valve is opened and air will be pumped into the low pressure receiver but not into the high pressure receiver.

5. In an air compressor the combination 10 of a low pressure cylinder having an intake and discharge, a high pressure cylinder having an intake and discharge, a connection between the discharge of the low pressure cylinder and the intake of the high pressure cylinder, a low pressure receiver connected with said connection between the cylinders, a high pressure receiver connected with the discharge of the high pressure cylinder, a return-pass between the connections to the 15 low and high pressure receivers, a stop-valve in said return-pass, electro-magnetic means controlled by the pressures of air in the high and low pressure receivers and controlled by the temperature of the compressed air, for controlling the opening and closing of said stop-valve, and a back-check-valve in the connection between the discharge of the high pressure cylinder and the high pressure receiver beyond the point of 20 connection of the return-pass, whereby when the pressure in the high pressure receiver rises above normal or the pressure in the low pressure receiver drops below normal or the temperature of the compressed air rises 25 above normal said stop-valve is opened and air will be pumped into the low pressure receiver but not into the high pressure receiver.

6. In an air compressor the combination 40 of a low pressure cylinder having an intake and discharge, a high pressure cylinder having an intake and discharge, a connection between the discharge of the low pressure cylinder and the intake of the high pressure cylinder, a low pressure receiver connected with said connection between the cylinders, a high pressure receiver connected with the discharge of the high pressure cylinder, a return-pass between the connections to the 45 low and high pressure receivers, a stop-valve in said return-pass, electro-magnetic means

controlled by the pressures of air in the high and low pressure receivers and controlled by the temperature of the compressed air for controlling the closing and opening of said 55 stop-valve, means controlled by the speed of the compressor for controlling said pressure and temperature controls, and a back-check-valve in the connection between the discharge of the high pressure cylinder and the 60 high pressure receiver beyond the point of connection of the return-pass, whereby when the speed of the compressor is slow said stop-valve is opened.

7. In an air compressor the combination 65 of a low pressure cylinder having an intake and discharge, a high pressure cylinder having an intake and discharge, a connection between the discharge of the low pressure cylinder and the intake of the high pressure 70 cylinder, a low pressure receiver connected with said connection between the cylinders, a high pressure receiver connected with the discharge of the high pressure cylinder, a return-pass between the connections to the 75 low and high pressure receivers, a stop-valve in said return-pass, electro-magnetic means for controlling the closing and opening of said stop-valve, means controlled by pressure connected with the high pressure receiver 80 for controlling the said magnetic means, means controlled by pressure connected with the low pressure receiver for controlling said magnetic means, means controlled by temperature connected with the high pressure 85 receiver for controlling said magnetic means and means controlled by the speed of the compressor for cutting in and out said high pressure, low pressure and thermostatic controlling means, whereby said stop-valve will 90 be opened by excess pressure in the high pressure receiver, by abnormally low pressure in the low pressure receiver, by undue temperature in the high pressure receiver and by low speed of the compressor, the connections being made in such manner that the pressure and temperature controlling means cannot close said stop-valve unless the compressor is running at a predetermined speed.

EBENEZER HILL.
